JAMES M. COLEMAN AND KARL F. NYSTROM, OF MONTREAL, QUEBEC, CANADA.

CLASP-BRAKE.

1,385,607.

Specification of Letters Patent. Patented July 26, 1921.

Original application filed May 31, 1917, Serial No. 172,130. Divided and this application filed December 26, 1917. Serial No. 208,909.

To all whom it may concern:

Be it known that we, JAMES M. COLEMAN, a citizen of the United States, and KARL F. NYSTROM, a subject of the King of Sweden, both residing at the city of Montreal, in the Province of Quebec and Dominion of Canada, have invented certain new and useful Improvements in Clasp-Brakes, of which the following is a full, clear, and exact description.

This invention relates to improvements in clasp brakes for railway car trucks, being a division from application Serial No. 172,130, filed May 31, 1917, and the object of the invention is to provide a clasp brake of great simplicity of construction.

A further object is to provide as far as possible for the use of exactly similar parts, in order that construction and maintenance may be effected at a minimum cost.

A still further object is to provide improved anchoring and adjusting means for the brake, which will substantially eliminate tampering therewith.

Another object is to provide suspension means for the brake beams, which will insure their movement substantially in a horizontal plane when the brakes are applied or released.

Broadly speaking, the invention consists of a series of suitable brake beams carrying the brake heads. Each of these beams is provided with a double suspension, so designed that the beam travels substantially in a horizontal plane. Release springs are provided to normally hold the shoes away from the wheels. A system of links and levers is provided connecting all the brake beams, and is so arranged that the braking force is distributed uniformly between all the brake shoes of the truck.

In the drawings which illustrate the invention:-

Figure 1 is a plan view of a truck equipped with brakes according to the present invention, certain of the elements being omitted for clearness.

Fig. 2 shows on the left an elevation, and on the right a central longitudinal section of a truck showing the arrangement of brake gear.

Fig. 3 is an enlargement of the brake gear shown in the right hand portion of Fig. 2.

Fig. 4 is a perspective view of one of the release springs and its mounting.

Fig. 5 is a perspective view, illustrating one of the brake rod guide brackets and one of the brake hanger guide brackets.

Fig. 6 is a perspective view of the anchor bracket showing the method of anchoring.

Referring more particularly to the drawings, 11 designates transverse members of the truck frame, certain of which are downwardly offset in their central portions for reasons which do not concern the present

application, and 12 the wheels. Brake beams 13 are provided arranged in pairs for each pair of wheels. These beams are each provided at each end with a brake head 14, which carry brake shoes 15 in the usual manner.

The brake beams are suspended at the ends by links 16 which pass through the brake heads and are supported in brackets 17 secured to the transverse truck frame members. Each brake beam is in addition provided intermediate its ends with a balance arm 18, which is connected at its extremity by a link 19 with a balance spring 20 connected to the truck frame. These balance springs are uniform throughout the

truck and are each bent intermediate their ends so that they may be attached in normal position to the straight frame members and in inverted position to the offset frame members and have their free ends all in the same

horizontal plane and all the same distance above the brake beams. It will be clearly seen in Figs. 2 and 3 that the suspension links 16 and balance links 19 are arranged at a slight incline to the vertical, and are also slightly out of parallel, and further, that the pivotal points of the suspension links are on higher horizontal planes than corresponding pivotal points of the balance links.

This disposition, combined with the dimensions of the links, is such that the brake beams will travel in a substantially horizontal plane instead of in a curved plane, as is ordinarily the case. It will further be seen that the double suspension

holds the brake beams rigidly against rotating about their longitudinal axes. These seemingly trivial points are of great importance in the satisfactory operation of the brakes.

When brake beams travel in curved planes, it follows that the shoes are tilted as they wear, and also that very frequently, the shoes do not press squarely against the wheels, thus causing a slight rotation of the brake beam on its axis with

consequent unnecessary stress to the mechanism. The arcuate movement of the brake beams is responsible for the uneven wear of brake shoes. The result may be described as follows:—A new shoe on insertion touches the wheel at its upper end first, and consequently the greatest wear is at this point. As the shoe wears, a full bearing surface on the wheel is obtained. 5 Further wear necessitates further movement of the brake beam and its arcuate movement finally presents the shoe, so that its lower end touches the wheel first and wear is now greater at this point. It frequently happens that during the entire life of a shoe, 10 the wear is greater at one end than at the other. By causing the brake shoe to move in a horizontal plane, as is done according to the present invention, the heads may be 15 adjusted to present a shoe squarely to the wheel, and this condition will obtain as long as the shoe is in use. Another disadvantage of the arcuately moving brake beam is the varying braking effect produced at different 20 periods of the shoe's life. According to the present invention, the braking effect will be uniform throughout the entire life of the shoe. 25

In order to normally hold the shoes out 30 of contact with the wheels, a release spring 21 is located near each end of each brake beam. These springs are C-shaped, one extremity of each being connected to a transverse frame member and the other extremity to the brake beam directly or through 35 the medium of a bracket 22. One extremity at least of each spring is provided with a series of apertures 23, so that its point of connection may be varied according to the 40 tension desired. The springs are uniform throughout the truck, those connected to the straight frame members being connected directly to brake beams, and those connected to the offset frame members being connected 45 to the brake beams by means of the brackets 22.

The brake beams are moved in the horizontal plane previously referred to by means 50 of a mechanism which distributes the braking force uniformly between all the shoes. To this end, force applying mechanism is disposed at each side of the truck, so as to connect with the brake beams close to the brake heads. The mechanisms on each side 55 of the truck are connected by an evener 24, which receives the braking force through a link 25 connected in the center of the evener. The force applying mechanism on each side of the truck comprises a series of levers 60 26 and a series of links 27 and 28, together with special terminal links 29 and 30. The levers 26 are each connected at the lower extremity to a brake beam by means of suitable brackets 31. These levers are arranged in pairs for each wheel, as clearly shown,

and the levers of each pair are connected intermediate their extremities by links 28. The upper extremity of a lever of one pair is connected to the upper extremity of the adjacent lever of the next pair by a link 27. 70 One extreme end lever of the series is connected by a link 29 with the evener 24, and the upper extremity of the other extreme end link of the series is connected to an anchor link 30. One extremity of the link 29 75 is formed into an eye 32 for attachment to the evener, this eye being horizontally disposed. This link 29 is supported in the truck and guided by a bracket 33 shown in Fig. 5, which is provided with a vertical 80 elongated eye 34, through which the link 29 passes. This arrangement is for a two-fold purpose, first, it permits vertical play of the link as the wheels move in the truck, and secondly, it necessitates the link 29 being inserted through the bracket with its eye 32 85 in vertical position, and then turned on its axis, and subsequently connected to the lever 26. It will thus be seen that the eye 32 holds the link 29 against disconnection from the 90 bracket. The brackets which support the links also obviously give support to the evener 24.

The anchor link 30 at the opposite end of each series is the point at which adjustment 95 is made to provide for uniform movement of the systems at opposite sides of the truck. In order to prevent this adjustment being tampered with, the link which is threaded on its free end is passed through an anchor casting 35, and is provided with a U-shaped nut 36, which embraces the anchor casting and is thus held from turning on the link. The only way in which adjustment can be made is to disconnect the link from the end 100 lever of the series to which it is attached and rotate it in the nut, and then re-connect it with the lever. This entails such an amount of work that it will not be lightly undertaken. The arrangement furthermore 105 provides for an absolute locking of the nut, so that the adjustment once made is permanent. 110

The links 27 are provided with guides 37 secured to the truck frame, which permit all 115 the vertical movement necessary, but hold the links against lateral movement.

From the foregoing description and the drawings, it will be noted that there is a very small number of different parts. 120 Wherever possible, parts performing the same functions in different portions of the truck have been made exactly similar. For example, the twelve levers 26 are exactly alike, also the six links 28. The twelve return springs are alike, the different conditions of their use being provided for by means of eight exactly similar brackets. The construction offers sufficient obstacle to practically preclude tampering with the ad- 130

justment of the brakes, and at the same time is sufficiently simple, so that it may be easily adjusted by those properly authorized. It will be noted that the pivots which must be removed for these adjustments are readily accessible. The series of apertures in the return springs permits individual adjustment to allow for variations in temper and the like, and permit the resistance to the braking force to be regulated to absolute uniformity throughout the truck, which uniformity is extremely important in a clasp brake. The arrangement of the links 29 has the additional advantage that each truck is a complete unit in itself, and can be removed from a car by simply disconnecting the evener from the link 25.

While the invention has been shown and described as applied to a six-wheel truck, it will be obvious that it may be applied equally well to a truck having a greater or lesser number of wheels.

Having thus described our invention, what we claim is:—

1. In a brake gear for use in trucks having transverse frame members at different heights, balance springs bent intermediate their ends whereby they may be attached in normal position to the upper level frame members or in inverted position to the lower level frame members, while maintaining the free extremity in a single horizontal plane.

2. In a brake gear for use in a truck having frame members on different horizontal planes, brake beam balance springs arranged at a common inclination such that the free extremities of those attached to the upper frame members and those attached to the lower frame members lie in the same horizontal plane.

3. For use in a truck having frame members on two horizontal planes, a brake gear, including brake beams, suspension means therefor, balance arms fixed to the brake beams and extending in the plane of the brake beams, balance springs connected to the upper and lower frame members, and links of uniform length connecting said balance springs with the balance arms.

4. For use in a truck having upper and lower frame members, a brake gear, including brake beams, and release springs, said springs being each connected at one end to a frame member, and at the opposite end to a brake beam, and fillers interposed between the brake beams and those release springs connected to the lower frame members.

5. A brake gear according to claim 7, in which each of the release springs is provided at the end connected to the brake beam with a series of attaching apertures whereby the springs may be adjusted so that all have equal tension.

6. In a clasp brake gear the combination

with a truck frame and brake beams of brackets secured to the truck frame uniform distances above the brake beams, brake beam hangers supported by said brackets with their free ends all in the same horizontal plane, balance springs each connected at one end to the truck frame and having their free ends in the same horizontal plane, balance arms of equal length connected to the brake beams and located in a single horizontal plane, links connecting the balance springs and balance arms, release springs connected to the brake beam and connected at different levels to the truck frame and fillers between the brake beams and those release springs connected to the truck frame at the lower levels whereby said parts may be of uniform dimensions and interchangeable.

7. A clasp brake gear including a system of force applying levers and links and means arranged to hold the entire system in operative relation to the truck carrying it during separation of such truck from a car.

8. A clasp brake gear comprising brake beams, and a series of operating links and levers therefor including an actuating link, and an anchor link, designed to pass through the end frame of a truck, and a U shaped nut on the anchor link embracing the truck end frame and holding the gear to the truck against the effect of the operating force.

9. A clasp brake gear comprising brake beams, and a series of operating links and levers therefor including an actuating link, a guide member for the actuating link having a vertically disposed slot for the passage of the link, and an eye on the extremity of said actuating link disposed in a horizontal plane, and normally holding the link against withdrawal from its supporting bracket and limiting the releasing movement of the gear.

10. In a clasp brake gear, the combination with a pair of wheels, of a brake beam on each side of the axis of said wheels, brake heads on said brake beams, double suspension means for each of said brake beams, comprising a pair of hangers connected to the brake heads and a hanger connected directly to the beam and force applying means connected to the brake beams adjacent each end thereof.

11. In a clasp brake gear, the combination with a pair of wheels, of a pair of brake beams arranged one on each side of the wheel pair axis, a three point suspension for each of said beams holding the same against movement in an arcuate path, and force applying mechanism connected to each end of each beam.

12. In a brake, the combination of levers and pull rods, one complete set of which is located at each side of a truck, a beam or bar connecting the two sets of riggings and a

support for said rigging located intermediate the length of said bar.

13. In a brake, the combination of brake levers and connecting rods, one complete set of which is located at each side of a truck, whereby said levers are connected and apply their force at a point close to the brake shoes, beams or bars connecting the riggings on opposite sides on the truck, and supporting elements connected to said beams at a point intermediate their ends and located substantially as described.

14. In a brake arrangement, the combination of heads carrying shoes, a brake bar connecting adjacent heads, a brake rigging located at each side of the truck and connected to said brake bars at a point close to said head, and supporting means for said riggings and bars applied directly to said bars at a point substantially on the longitudinal center line of the truck, substantially as described.

15. In a brake, the combination of brake heads and shoes applied to both sides of each pair of wheels, a brake bar connecting said heads, and a brake rigging at each side of said truck, the brake levers of which rigging are connected to said brake bars at a point close to said brake heads, the brake levers at an extreme end of the truck, being anchored to the truck, whereby the pull is from the opposite end of the truck, guiding means applied to said riggings and supporting means applied to said brake bars, substantially as described.

16. In a brake rigging, the combination of beams, brake heads carried adjacent the extremities thereof, suspension links for movably connecting the heads to truck portions, members mounted on the beams intermediate the heads, supporting members carried by truck portions and associated with the first mentioned members to afford supporting and path determining means for the beams, and power transmitting devices supported by the beams at points intermediate the heads and the first mentioned members.

17. In a brake rigging, the combination of beams, brake heads carried adjacent the extremities thereof, suspension links for operatively connecting the heads with truck portions, members carried by the beams intermediate the heads, supporting members associated with the truck and the first mentioned members to provide supporting and path determining means for the beams, yielding pressure means to urge the beams to inoperative position, and power transmitting devices having operative association with the beams intermediate the heads and the first mentioned members.

18. In a brake rigging, the combination of beams, brake heads carried adjacent the extremities thereof, power transmitting devices operatively associated with the beams adjacent the heads, suspension members for operably connecting the heads to truck portions, and supporting members sustained by a truck portion and movably associated with the beams, said supporting members having connection with the beams to provide supporting and path determining means for the beams.

19. In a brake rigging the combination with beam members, of brake heads carried adjacent the extremities thereof, suspension members for operably connecting the heads to truck portions, power transmitting members operably associated with the beams adjacent the heads, resilient members having support upon truck portions, and means carried by the beams spaced on the beams from the power transmitting members operably associated with said resilient members to provide supporting and path determining means for the beams.

In witness whereof, we have hereunto set our hands in the presence of two witnesses.

JAMES M. COLEMAN.
KARL F. NYSTROM.
